UNITED STATES PATENT OFFICE.

L. F. FRAZEE, OF SOUTH AMBOY, NEW JERSEY.

IMPROVEMENT IN LIFE-RAFTS.

Specification forming part of Letters Patent No. 56,201, dated July 10, 1866.

To all whom it may concern:

Be it known that I, L. F. FRAZEE, of South Amboy, Middlesex county, State of New Jersey, have invented a new and Improved Life-Raft; and I do hereby declare that the following is a full, clear, and exact description thereof, which will enable others skilled in the art to make and use the same, reference being had to the accompanying drawings, forming part of this specification, in which—

Figure 1 represents a plan or top view of this invention. Fig. 2 is a longitudinal vertical section of the same. Fig. 3 is a transverse section of the same.

Similar letters of reference indicate like parts.

This invention relates to a life-raft which is so constructed that it can be easily carried on board of steamboats or vessels of any description, and that the same when thrown overboard will always float right side up and be ready to receive a number of passengers. It is composed of two air-tight hollow drums, which are protected by wooden cases and connected to each other by cross-braces, so as to give room for passengers. The space between the drums is partially filled with cork or other buoyant material, and both sides of the raft are alike, so that it is immaterial which side turns up when said raft is launched.

A represents my life-raft, which is constructed of two hollow drums, B, of sheet metal or other suitable material, and of such a size that their displacement is equal to the load to be carried. Said drums are protected by wooden cases C, and the ends of these cases are made of solid wood, so that the drums are prevented from being stove in or injured if the raft comes in contact with a vessel or other obstruction.

The two drums are connected together by cross-bars D, which are secured to the same by copper straps E, and the space between the drums is occupied by two seats, F, extending throughout the entire length of the raft, with sufficient room between for the legs of the persons occupying said seats.

Suitable rails G are hinged to the seats, so that the same can be turned up and made to form the backs for the seats, and also a protection for the passengers.

The space under the seats is filled with cork or other buoyant material, so as to render the raft capable to float even if one or both of the drums should be injured or stove in.

Near the bow of the raft a mast, H, is secured in such a manner that the same can be turned down when the raft is not used and up when the raft is to be used. When the mast is up it is held in position by suitable ropes and lines, and a sail, I, is hoisted on it, so that the raft can be sailed with ease and convenience.

Boards J, which are made to turn up to an inclined position at the bow and stern of the raft, form a sort of protection against the sea and enable the raft to pass through a pretty rough sea without shipping much water. Through the board at the stern a paddle, K, may be placed, which serves as a rudder if the raft is rigged up and under headway.

By these means a life-raft is obtained which is not liable to get leaky or out of order when exposed to the sun or atmosphere for a long time, and which is so constructed that it can be launched, or rather thrown overboard, by inexperienced persons without danger of swamping or filling, and consequently all the disadvantages of an ordinary boat are avoided.

My raft takes up comparatively little room, and it can be easily made large enough to support twenty or thirty persons. An article is thus obtained which is of incalculable value for ferry-boats and passenger-steamers on inland waters and on the ocean, and in fact for vessels of any description, and which will prove the means of saving a great many lives which with the ordinary means, or rather want of means, would be lost.

What I claim as new, and desire to secure by Letters Patent, is—

The combination of the drums E and casings C, as described, cross-bars D, and hinged rails G, all constructed and arranged in the manner and for the purpose herein specified.

LAWRENCE F. FRAZEE.
